FREDERICK SINDINGCHRISTENSEN, OF BROOKLYN, NEW YORK, ASSIGNOR
OF ONE-HALF TO FRANCIS F. STORM, OF MAYWOOD, NEW JERSEY.

ELECTRIC-ARC LAMP.

SPECIFICATION forming part of Letters Patent No. 752,005, dated February 9, 1904.

Application filed August 29, 1902. Serial No. 121,444. (No model.)

To all whom it may concern:

Be it known that I, FREDERICK SINDING-
CHRISTENSEN, a subject of the Crown of Den-
mark, and a resident of New York city, bor-
5 ough of Brooklyn, county of Kings, and State
of New York, have invented certain new and
useful Improvements in Electric-Arc Lamps,
of which the following is a specification, ref-
erence being had to the accompanying draw-
ings, forming a part thereof.

My invention relates to improvements in
electric-arc lamps, and particularly to im-
provements in devices for feeding and other-
wise operating the upper carbon thereof.

15 There are three essentials to the efficient op-
eration of an electric-arc lamp of the present
day. First, it is essential that the carbon
points or pencils shall be in contact when
there is no current through the lamp, this
20 for the reason that contact is required be-
tween the carbon pencils in order to complete
electric circuit when the line is first closed
through the switch; second, it is essential
25 to draw the carbon pencils apart after circuit
has been completed in order to establish an
arc, and, third, it is essential to feed the
upper and lower carbons together, as one or
both of the said pencils become disintegrated
30 at the points or worn away from use.

35 In feeding the carbon pencil to compensate
for loss it has been common heretofore to hold
the pencils stationary for a while until a cer-
tain amount has been burned away and then
to feed the upper pencil down for a short dis-
tance, to again hold it stationary, and so in-
termittently feed and hold the pencil during
the burning of the lamp. The ideal condi-
tions are of course an initial separating of the
40 carbon pencils the exact distance required to
make the best arc and subsequently a relative
feeding together of the pencils exactly in pro-
portion as the distance between the points
tends to become greater, thus maintaining at
all times a uniform arc.

45 The object of this my present invention is
to fulfil the foregoing conditions and to con-
stantly feed the upper pencil toward the
lower one exactly in proportion as the point

or points wear away or become disintegrated
to maintain a uniform arc.

50

I attain the foregoing by the employment
of a magnetic floating clutch and an electro-
magnet, preferably of the solenoid form, for
operating said clutch.

55 My invention further consists in certain
novel details of construction and combination
of parts, as hereinafter set forth.

I will now proceed to describe an electric-
arc lamp embodying my invention and will
then point out the novel features in claims.

60

65 In the drawings, Figure 1 represents a cen-
tral vertical section of an electric-arc lamp
embodying my invention; and Fig. 2 is a view
in central vertical section of the same, the
plane of section being taken at right angles
to the plane of section of Fig. 1.

In the construction represented in the draw-
ings a frame is provided comprising a dia-
phragm *a* and a strap *b*, by which the lamp as
a whole may be suspended. A solenoid *c* is
70 arranged upon the suspension-strap *b* and
may be adjustably secured thereto by angle-
brackets *d*, rigidly secured to the upper face
of the solenoid and slotted to receive bolts *e*,
tapped into the strap *b*. A brass tube *f*, con-
stituting a shield or receiver for the upper
carbon pencil *g*, surrounds the carbon pencil
above the diaphragm *a* and passes through
the solenoid *c*. Secured to the tube *f* at a
75 point within and in proximity to the solenoid
c is a soft-iron sleeve *h*, which with certain
connected parts constitutes the core or arma-
ture of the solenoid. The sleeve *h* is prefer-
ably wrapped around with a thin sheet of
soft-iron plate formed in blank in substantially
80 the shape of a right-angle triangle, so that
when wound several times around the said
sleeve the wrapping and the sleeve together
will form a tapered core, substantially as
85 shown. The sleeve *h* is further provided with
an iron clamp *i*, secured around the lower end
of the sleeve *h* and beneath the overwound
portion just described. Two oppositely-dis-
posed arms or levers *j*, also composed of iron,
90 are pivoted at their upper ends to the said
iron clamp and at their lower ends are adapted
95

to contact with the lower projecting end of the sleeve *h*. Two oppositely-disposed spring clamping-fingers *k* are pivoted at *l* to opposite sides of the tube *f*. The upper ends 5 of the spring clamping-fingers *k* engage, respectively, with the lower ends of the arms or levers *j* and tend to press them inwardly toward the sleeve *h*, while the lower ends of the spring clamping-fingers *k* engage the sides 10 of the upper carbon pencil *g*. The spring clamping-fingers *k* are preferably made of brass or other suitable non-magnetic material.

The lower carbon pencil *m* is suitably supported by an arm or bracket *n*, secured to the 15 diaphragm *a* of the frame, but insulated therefrom.

The electric connections are as follows: A wire *o*, leading from a source of electric supply, passes through suitable resistance to the 20 solenoid *c*. Thence current passes through a guide-collar *p*, secured to the solenoid or to the strap *b* and in sliding contact with the tube *f*, to the said tube *f*, and thence through the spring clamping-fingers *k* to the upper carbon 25 *g*. The current returns through the lower carbon *m*, its supporting bracket *n*, and negative wire *q*, back to the source of electrical supply.

The operation is as follows: Current supplied to the lamp will pass through the solenoid, energizing same and causing said solenoid to attract and lift its core or armature *h*, together with the connected parts, which comprise the tube *f*, the clamp *i*, the arms or levers *j*, and the spring clamping-fingers *k*. The arms or levers *j* being composed of soft or magnetic iron and being connected to the core or armature will be within the magnetic field and being of the same polarity as the 30 sleeve will tend to be forced outwardly or away therefrom. In moving outwardly they will act upon the spring clamping-fingers to force the lower ends thereof against the carbon pencil *g*, so as to hold or clamp same to the tube 35 *f*. When, therefore, the tube *f* is lifted under such conditions, the carbon pencil *g* will be lifted therewith. The extent of movement of these parts is limited by the clamp *i* coming in contact with the lower face of the solenoid *c*.

By the foregoing it will be seen that immediately after circuit is closed by a suitable switch in the line the carbon pencil *g* will be lifted up the required distance to form the 40 desired arc. As now the lower end of the carbon pencil *g* wears or burns away or becomes disintegrated the resistance at the arc will be higher and less current will pass through the solenoid. The magnetic field then becoming 45 weaker the arms or levers *j* will have less tendency to fly apart and will gradually approach the sleeve *h* until the weight of the carbon *g* will overcome the lessening frictional hold of the spring clamping-fingers and will be permitted to feed slightly downward. As

the carbon pencil *g* so feeds downwardly the resistance at the arc is lessened, the magnetic field strengthened, and the pencil again held by the spring clamping-fingers. By the foregoing a balance may be effected between the resistance at the arc and the pressure of the clamping-fingers, so that the carbon pencil may be fed downwardly exactly in proportion as it burns or otherwise wears away, and a uniform arc may be automatically maintained. 70 When circuit is finally broken, as by the opening of a switch in the line, the tube *f*, with the armature and its correlated parts, will fall, and the carbon pencil *g* will drop into contact with the carbon pencil *m*, so as to be in 75 proper condition for the next lighting of the lamp.

It is obvious that the device herein is capable of many modifications within the spirit and scope of my invention and that the foregoing is but one embodiment of the same. I 80 do not, therefore, desire to be limited to the precise details of construction and combination of parts; but

What I claim is—

1. In an electric-arc lamp, the combination 90 with a frame and an electromagnet supported thereby, of an armature for said electromagnet, and a magnetic clutch for the movable carbon of said lamp, comprising a moving member in magnetic connection with said armature but located at a point outside of the direct influence of attraction of said magnet and operated by the repulsive force exerted between the armature and moving member, 95 due to their similar polarity.

2. In an electric-arc lamp, the combination 100 with a frame and an electromagnet supported thereby, of an armature for said electromagnet, and a magnetic clutch for the movable carbon of said lamp comprising a plurality of moving members in magnetic connection with said armature but located at a point outside of the direct influence of attraction of said magnet and operated by the repulsive force 105 exerted between the armature and moving members, due to the similar polarity of the armature and the moving members.

3. In an electric-arc lamp, the combination 110 with a frame and a solenoid supported thereby, of a core or armature for said solenoid, and a magnetic clutch for the movable carbon of the said lamp comprising a movable member in magnetic connection with said core or armature but located at a point outside of the direct influence of attraction of said magnet and operated by the repulsive force exerted between the armature and moving member, due to their similar polarity.

4. In an electric-arc lamp, the combination 120 with a frame and a solenoid supported thereby, of an armature or core for said solenoid, and a carbon-clutch-operating lever of magnetic material, pivoted to the said core at a point beneath the said solenoid, and arranged 125

entirely outside thereof, said lever in magnetic contact with said core, whereby said lever constitutes a relatively movable portion of the said core but has the same polarity.

5 5. In an electric-arc lamp, the combination with a frame and a solenoid supported thereby, of an armature or core for said solenoid, and two oppositely-disposed carbon-clutch-operating levers of magnetic material, pivoted to the said core and in magnetic contact therewith, whereby said levers constitute relatively movable portions of the said core but have the same polarity.

6. In an electric-arc lamp, the combination with a frame and a solenoid supported thereby, of a core or armature for said solenoid, a plurality of levers of magnetic material, pivoted in magnetic contact with the said core, whereby said levers constitute relatively movable portions of the said core but have the same polarity, and clamping-fingers engaging said levers, but magnetically insulated therefrom, and adapted to engage the sides of the movable lamp-carbon.

25 7. In an electric-arc lamp, the combination with a frame and a solenoid supported thereby, of an armature or core for said solenoid, a plurality of levers of magnetic material, pivoted in magnetic contact with the said core, whereby said levers constitute relatively movable portions of the said core but have the same polarity, and spring clamping-fingers engaging said levers, and adapted to engage the sides of one of the lamp-carbons.

35 8. In an electric-arc lamp, the combination with a frame and a solenoid supported thereby, of an armature or core for said solenoid, a plurality of levers of magnetic material, pivoted in magnetic contact with the said core, whereby said levers constitute relatively mov-

able portions of the said core but have the same polarity, and spring clamping-fingers of non-magnetic material engaging said levers, and adapted to engage the sides of one of the lamp-carbons.

45

9. In an electric-arc lamp, the combination with a frame and a solenoid supported thereby, of a carbon shield or holder arranged to pass through the said solenoid, a core or armature surrounding the said shield or holder within, and in proximity to, the said solenoid, levers *e* of magnetic material and pivoted in magnetic connection with said core, and spring clamping-fingers of non-magnetic material pivoted to said shield or holder, and at 55 their upper ends engaging the said levers, and at their lower ends adapted to engage the sides of the upper lamp-carbon.

10. In an electric-arc lamp, the combination with a frame and a solenoid supported thereby, of a carbon shield or holder arranged to pass through the said solenoid, a tapered core of magnetic material surrounding the said shield or holder at a point within, and in proximity to, the solenoid, a plurality of levers *e* pivotally mounted in magnetic connection with said core, and a plurality of spring clamping-fingers *f* of non-magnetic material, pivoted to said shield or holder, the upper ends of which bear against the levers *e* and 60 tend to press them inwardly toward the core, and whose lower ends bear against that carbon of the lamp adapted to be received within the shield or holder, the said solenoid and carbon adapted to be connected electrically in 65 series in a line-circuit.
